UNITED STATES PATENT OFFICE.

HENRI ROSIER, OF LA PRÉALLE-HERSTAL, BELGIUM.

AUTOMATIC PISTOL.

970,645.

Specification of Letters Patent. Patented Sept. 20, 1910.

Application filed November 18, 1908. Serial No. 463,273.

To all whom it may concern:

Be it known that I, HENRI ROSIER, subject of the King of Belgium, residing at La Préalle-⁴ Herstal, Belgium, have invented certain new and useful Improvements in Automatic Pistols; and I hereby declare the following to be a full, clear, and exact description of my invention.

The present invention relates to an automatic pistol having a fixed barrel and a non-sliding casing, the same being arranged so that the frame or body does not directly receive the shocks due to the recoil, which permits of considerably simplifying the manufacture of said body and reducing the cost of same. The trigger, firing and disengagement mechanisms are also greatly simplified.

The accompanying drawing represents a pistol of this type.

Figure 1 is a side elevation of the pistol without the cover plates of the handle. Fig. 2 is an end view. Fig. 3 represents a longitudinal section of the pistol when closed. Fig. 4 is a transverse vertical section on line A—A. Fig. 5 shows a longitudinal section on B—B. Fig. 6 shows, in section, the body separately, with the barrel and ejector. Fig. 7 is a plan of the parts shown in Fig. 6, and Fig. 8 is a rear view of same. Fig. 9 represents the bolt separately in end-view, elevation and plan. Fig. 10 shows, in elevation and plan, the trigger and the connecting bar or stirrup for acting on the sear. Fig. 11 shows the sear separately. Fig. 12 represents the plug or closure piece for securing the firing spring within the breech-bolt.

The pistol consists of a frame or body 1 which carries the barrel 2, surrounded by the sleeve 3 of the cover hood or casing 4 which forms the upper part of the arm. This cover or casing 4 is perforated throughout its length and contains the breech-bolt return spring 5 which bears, at its inner end, against an internal flange or shoulder 6 of said casing 4, and at its front end, against the head 7 of a rod 8, whose rear end is screwed into the upper part 9 of the bolt 10 (Figs. 3 and 9). This bolt is provided with two lateral tongues 11, which engage within corresponding longitudinal grooves 12, in the body 1. The bolt 10 is also guided in the said body 1 and is capable of moving alternately backward and forward.

The head 9 of the bolt 10 extends along

the top of the body 1, and slides, by its two faces 13, on the upper face of the said body and further, it is constantly forced toward the rear end of the casing 4 by means of the re-action spring 5. The pressure exerted by the spring 5 on the shoulder 6 of the casing 4 also has the effect of forcing the latter rearward and holding it against the body 1.

The external side faces of the head 9 of the bolt are channeled or grooved, so as to be capable of being easily taken hold of by the shooter.

The lower part of the bolt 10 is provided with a longitudinal chamber which is closed by a removable plug 17, and serves to contain the firing pin 14; the latter being provided, at the rear end, with a projection 15, wherewith the sear engages when the arm is cocked, as hereinafter described. The firing spring 18 is arranged between the plug 17 and the firing pin 14 in such a manner that it constantly tends to force the latter forward.

The lock mechanism comprises a sear 16, pivoted on a pin 19 carried by the body and having its nose arranged in the path of the movement of the projection 15 on the firing pin; the said sear being constantly pressed toward the rear by a spring 20 which is held in place by the pin 22 and causes the lower arm of the said sear to bear against the rear wall of the body. The said sear is provided with an arm 31 lying partially against the magazine, and also carries, at its front, a lever 23 which is pivotally supported by the pin 24, and is maintained, by a small spring 25 against a stop or abutment formed on the sear to limit its forward movement.

The trigger 26 is pivoted to the body 1, and is provided with a spring 28 which tends to maintain it in its forward position. The sear-operating arm or bar 29 is made in one piece with the trigger 26, or is rigidly fixed to the latter by a screw 30 or other suitable means (Figs. 3, 5 and 10). This arm 29 passes along the one side of the magazine, and its end comes immediately under the arm 31 of the sear, in such a manner that the latter is turned when the trigger is pressed, as hereinafter described.

The bolt 10 carries, as usual, the extractor 32, while the body 1 carries, on one of its interior faces, the ejector 33 for effecting

the ejection of the cartridge shells through the opening 34 in the opposite face of the body 1. This ejector 33 consists of a spring, fixed to the body 1, near its front end, at 6 39, and provided at the rear end, with a nose 35 projecting into the interior of the body 1; it is also guided in the body 1 by a projection 36 engaging within a corresponding hole made in the walls of the body. The 10 bolt 10 is provided, upon the side corresponding to the ejector, with a groove 37, which is adapted to freely pass over said ejector. The head of the bolt 10 is provided with the back-sight. It follows from this 15 arrangement that the casing 4 and the bolt 10 are kept in place without it being necessary to employ special fastening devices; after having detached the rod 8 from the head 9 of the bolt 10, the said rod 8, the casing 4 and bolt 10 can be removed separately. The body 1 will then be completely stripped and readily accessible. The assembling is 20 accomplished without the aid of any tool.

25 The magazine for containing the cartridges, is located, as usual, in the butt or handle of the pistol, where it is fixed by means of a suitable catch, that can be readily disengaged by hand. In the arrangement 30 represented, the magazine is guided, and its replacement is facilitated, by a transverse pin 38 crossing the handle.

In order to fire the first shot, the shooter 35 has to draw the bolt rearward, and compress the spring 5. By this operation, the projection 15 of the firing pin, being taken rearward with the bolt, is made to cover the nose 21 of the sear 16, which is thereby turned upon its pivot. Then during the forward return of the bolt 10, (which effects the loading of a cartridge into the chamber of the barrel) the part 15 is engaged and held back by the nose 21 of the sear 16, 40 whose lower arm is pressed against the body 1, while the spring 5, restores the bolt to its forward position and thereby compresses the weaker firing spring 18. The firing mechanism is now cocked and the arm is ready for firing. A pressure exerted on the 45 trigger 26 will then cause the rigid bar 29 to rise, and act in its turn, on the arm 31 of lever 23, and consequently trip the sear 16, which, as it turns about its pivot tensions the spring 20. This has the effect of liberating the firing pin 14, which is thrown forward and fires the cartridge in the barrel. After the sear 16 has turned through a certain angle rearward the arm 31 of the small 50 lever 23 disengages itself from the bar 29, so that the sear 16 can return to its forward position the forward end of the arm 31 being then below and bearing against the rear inclined surface of the bar 29, and the spring 25 being under some compression.

55 When the pressure on the trigger is removed

the spring 28 restores the parts 26, 29 to the positions shown in Fig. 3. During this movement the spring 25 acts to rock the member 23 to bring the arm 31 again into the position shown in said figure. This disengaging arrangement prevents a second or intentional discharge from taking place until after the shooter has released the trigger 26.

When, under the effect of the recoil produced by the firing of a cartridge, the bolt 10 is forced rearwardly at the same time that the empty cartridge shell is ejected, the head 75 of the rod 8 compresses the return spring 7 of the rod 8 compresses the return spring 5, so that the latter receives and cushions the 80 shock, which is only transmitted indirectly and with a greatly reduced force, to the body 1.

Having fully described my invention, what I desire to claim and secure by Letters 85 Patent is:—

1. The herein described pistol comprising a body, a fixed barrel, a reciprocating breech bolt carrying a firing pin, and a non-reciprocating, detachable casing surrounding the 90 barrel and abutting at its inner end against a portion of the breech bolt.

2. The herein described pistol comprising a body, a fixed barrel, a reciprocating breech bolt carrying a firing pin, a casing detachably surrounding the barrel, and a spring 95 arranged between an abutment on said casing and an abutment connected with the breech bolt and acting to hold the casing in position about the barrel and to cushion the 100 recoil of the breech bolt.

3. The herein described pistol comprising a body, a fixed barrel, a reciprocating breech bolt carrying a firing pin, a non-reciprocating casing surrounding the barrel and abutting 105 at its rear end against a portion of the breech bolt, a guide rod extending forwardly from the breech bolt into a chamber in said casing, and a coiled spring arranged within 110 said chamber about the guide rod and between a head thereon and an abutment within the casing.

4. The herein described pistol comprising a body, a fixed barrel, a reciprocating breech bolt carrying a firing pin, a detachable casing 115 surrounding the barrel, a rod detachably connected with the breech bolt and extending into a chamber in said casing, and a coiled spring within said chamber and surrounding said rod between an abutment 120 thereon and an abutment on the casing, said spring acting to hold the breech bolt and casing together and constituting the sole means for maintaining the casing in position on the barrel.

5. In an automatic or repeating pistol, the combination of a body, a barrel, a sliding breech bolt, the rearward movement of which is not directly obstructed by the body and a coiled spring acting to hold the breech 130

bolt in its forward position and constituting the only check to rearward movement of said bolt.

6. In an automatic or repeating pistol, the combination of a body, a barrel fixed to the body, a sliding breech bolt extending from the barrel and constituting the rear end of the upper part of the pistol, a casing supported by the barrel, and a coiled spring arranged between a relatively stationary abutment and an abutment connected with the breech bolt and adapted to hold the breech bolt in its forward position and to control and completely check recoil movements of said bolt.

7. In an automatic or repeating pistol, the combination of a body, a barrel, a sliding breech bolt, and a yielding means arranged entirely in advance of the rear end of the breech bolt for entirely controlling and limiting rearward movement of said bolt.

8. The herein described pistol comprising

a barrel, a reciprocating breech bolt, a body supporting the barrel and bolt and offering no obstruction to the rearward movement of the bolt, and a coiled spring arranged between abutments connected respectively with the breech bolt and body.

9. The herein described pistol comprising a barrel, a reciprocating breech bolt, a body supporting the barrel and bolt and offering no obstruction to the rearward movement of the bolt, a casing supported on the body in advance of the breech bolt, and a coiled spring arranged within said casing and connected with the breech bolt to check recoil movement thereof.

In testimony whereof I affix my signature in presence of two witnesses.

HENRI ROSIER.
